UNITED STATES PATENT OFFICE

RAYMOND G. MOORE AND ARTHUR CLAUD-MANTLE, OF BRIDGEPORT, CONNECTICUT, AS-SIGNORS TO THE BASSICK COMPANY, OF BRIDGEPORT, CONNECTICUT, A CORPORATION OF CONNECTICUT

ANTIRATTLE DOVETAIL FOR DOORS

Application filed July 30, 1930. Serial No. 471,695.

The present invention relates to improvements in self-adjusting anti-rattle dovetails, particularly for automobile doors, an object being to provide a device of this character which will prevent the rattle usually resulting from the vibration and weaving of the doors, effectually retaining the same against vertical movement, while at the same time compensating for lateral movement and wear. In the usual type of dovetail a socket member is provided having vertically yieldable dovetail members between which a wedge piece is engaged, and while these tended to dampen the vibration they did not effectually prevent it. It is particularly proposed to provide a device in which a socket member is provided with laterally adjustable resiliently supported dovetail members adapted to have a wedge member engaged between them, the respective dovetail members being supported against vertical movement. Another object is to provide such a device which will compensate for wear and also for variations in the vertical and lateral alignment of the door.

Another object is to provide a device which while holding the door against vertical vibrations will exert an outward force on the same in such manner that the latch of the door is held firmly against the striker plate and upon release of the latch will press the door open.

A further object is to provide a device constructed of few parts which may be assembled with facility, and which will be reliable and efficient in operation.

A still further object is to provide a device in which the dovetail members will be protected from excessive wear and breakage, and may be made of a self-lubricating substance, such as fibre, bakelite or the like, to the end that the device will have a long life, and the necessity for lubricating the same will be eliminated.

With the above and other objects in view an embodiment of the invention is shown in the accompanying drawing, and this embodiment will be hereinafter more fully described with reference thereto, and the invention will be pointed out in the claims.

In the drawing:

Fig. 1 is a perspective view of the outer side of the dovetail socket, according to the present embodiment of the invention, and which is shown mounted on the door frame.

Fig. 2 is a perspective view of the end of the door showing the wedge member mounted thereon, the door being shown in dotted lines, while the wedge member is shown in full lines.

Fig. 3 is a front elevation of the wedge member.

Fig. 4 is an edge view thereof.

Fig. 5 is a front elevation of the socket member.

Fig. 6 is a similar view and showing the wedge member in cross section engaged therein.

Fig. 7 is a rear elevation of the socket member.

Fig. 8 is a sectional view taken along the line 8—8 of Fig. 5.

Fig. 9 is a sectional view, taken along the line 9—9 of Fig. 5.

Fig. 10 is a plan view of the inner member of the casing.

Fig. 11 is a perspective view of one of the block members employed.

Similar reference characters indicate corresponding parts throughout the several figures of the drawing.

Referring to the drawing, the device, according to the present embodiment of the invention, comprises a socket member adapted to be secured to the door frame 10 within a suitable cut-out recess, and a wedged member adapted to be secured to the edge of the door 11 in relation to enter the socket member upon closing of the door.

The casing of the socket member comprises an outer part consisting of a face plate member 12 preferably formed of sheet metal, having a flange 13 at its forward edge bent inwardly at a right angle, and a lip 14 bent forwardly from the flange 13. A rearwardly converging opening 15 is provided in the face plate and extends across the flange 13 to the lip 14, the forward portion of the opening having its upper and lower edges disposed in parallel relation. An inwardly bent rim flange 16 is formed at the upper and lower

and rear edges of the face plate, and screw holes 17 having counter-sink flanges 18 are provided near the upper and lower edges.

The inner or box part of the casing formed 5 from sheet metal and, as shown in Fig. 10, comprises a rectangular portion 19 having wall flanges 20, bent from its upper and lower and rear edges, and outwardly extending base flanges 21 bent from the wall flanges, 10 the dimensions of these flanges being such that in the assembled relation, as shown in Fig. 7, they will be fitted within the rim flange 16 thus accurately positioning the box portion with respect to the opening 15 of the 15 face plate. The upper and lower base flanges have suitable cut-outs 22 for clearing the countersink flanges 18 of the screw holes. The base flanges are secured to the face plate by spot welding at suitable points, as at 23. 20 The depth of the rim flanges 16 and the countersink flanges 18 corresponds to the metal thickness of the base flanges 21, so that in the assembled relation a solid double-thickness reinforced face plate structure is provided. 25 The box portion 19 is flush with the lip 14.

A pair of inwardly bent lugs 24 are struck from the rear wall flange of the casing for supporting the ends of the springs, presently to be more fully referred to.

30 A pair of opposed block members 25 of generally rectangular shape are disposed within the casing, these blocks having flat parallel surfaces 26 adjacent the inner ends in sliding engagement with each other, and cooperating 35 with the upper and lower parallel walls of the casing to prevent vertical displacement of the blocks. Inclined slightly arcuate faces 27 extend from the flat faces 26 to the forward ends of the blocks in diverging relation to each other. Pockets 28 are provided 40 in the rear walls of the blocks within which are engaged coil springs 29 positioned upon the lugs 24 of the casing, and which press the blocks forwardly against the flange 13, as 45 shown in Fig. 5, while permitting the blocks to be forced laterally inwardly, as shown in Fig. 6. In both positions the inclined faces 27 are projected into the opening 15.

The blocks are preferably assembled within 50 the casing through the opening 15, this being done conveniently by first inserting one of the blocks and its spring, and then inserting the other block and its spring, pressing the first block inwardly while the second block is being inserted. The blocks may be of any suitable material, and because of the protection against breakage afforded by the casing, may be of fibre, bakelite, or other suitable squeak preventing, self-lubricating material.

The wedge member comprises an attaching base 30 having screw holes 31, and a rigid projecting wedge-shaped projection 32, having 55 flat inclined sides 33, substantially corre-

sponding to the inclination of the dovetail blocks.

The slightly arcuate shape of the inclined surfaces of the blocks permits firm engagement of the wedge member irrespective of slight variations in the vertical alignment of the door. Obviously this arrangement may be reversed, if desired, and the inclined surfaces of the wedge member made slightly arcuate, the inclined surfaces of the blocks being flat. 75

The operation is as follows:—

When the door is in open position the blocks are projected forwardly against the flange 13 of the casing as indicated in Figs. 1 and 5. As the door is closed the wedge member 32 engages between the blocks, contacting therewith before the door is completely closed, the complete closure of the door causing the blocks to be moved laterally against the pressure of the springs, which hold the blocks snugly against the wedge member, while the inclination of the engaging surfaces is such that vertical pressure will not displace the blocks and cause vibration. 90

The door is provided with the usual latch not shown, which engages behind a striker on the door frame, and the present device is such that it permits the door to close sufficiently to allow the latch to operate, and thereupon exerts an outward pressure on the door to force the latch bolt tightly against the striker. Upon release of the latch the device exerts an opening pressure on the door. 95

Should the wedge member be out of alignment with the socket, due to sagging of the door or inaccurate mounting of the wedge member, the independent movement of the respective blocks will permit them to adjust themselves to the wedge surfaces and perform their cooperative retaining function. 100

While we have shown the socket member on the door frame and the wedge member on the door, it will be obvious that this arrangement may be reversed, if desired. 110

We have illustrated and described preferred and satisfactory embodiments of the invention, but it will be obvious that changes may be made therein, within the spirit and scope thereof, as defined in the appended claims. 115

Having thus described our invention what we claim and desire to secure by Letters Patent is:—

1. In an anti-rattle device for doors, a socket member, and a wedge member adapted to be engaged therewith, said socket member comprising a casing having upper and lower confining walls, opposed wedge engaging elements confined between said walls and adapted to have sliding movement parallel to said walls, one of said elements slidably supporting the other, and said elements adapted to be moved laterally through engagement of said wedge member therebetween. 120

2. In an anti-rattle device for doors, a socket member, and a wedge member adapted to be engaged therewith, said socket member comprising a casing having upper and lower parallel confining walls, opposed wedge engaging elements confined between said walls and adapted to have sliding movement parallel to said walls, one of said elements slidably supporting the other, and said elements adapted to be moved laterally through engagement of said wedge member therebetween.

3. In an anti-rattle device for doors, a socket member, and a wedge member adapted to be engaged therewith, said socket member comprising a casing having upper and lower confining walls, laterally movable opposed wedge engaging elements confined between said walls, each having a portion adapted to engage the other to support it in relation to one of said walls and an inclined surface diverging with respect to the inclined surface of the other, and said elements adapted to be moved laterally through engagement of said wedge member between said diverging surfaces.

4. In an anti-rattle device for doors, a socket member, and a wedge member having inclined converging surfaces adapted to be engaged therewith, said socket member comprising a casing having upper and lower parallel confining walls, laterally movable opposed wedge engaging elements confined between said walls and having inclined diverging surfaces adapted to be engaged by the inclined converging surfaces of the wedge member and to be moved laterally thereby, said inclined surfaces of one of the members being convexly curved with respect to the inclined surfaces of the other whereby there is substantial line contact between them.

Signed at Bridgeport, county of Fairfield, and State of Connecticut, this 11th day of July, 1930.
